CLAIM

The ornamental design for a table light, as shown and described.

DESCRIPTION

FIG. 1 is a top, front, right perspective view of a table light showing my new design;

FIG. 2 is a bottom, front, right perspective view thereof;

FIG. 3 is a front elevational view thereof;

FIG. 4 is a back elevational view thereof;

FIG. 5 is a right elevational view thereof;

FIG. 6 is a left elevational view thereof;

FIG. 7 is an enlarged top plan view thereof; and,

FIG. 8 is an enlarged bottom plan view thereof.

The broken lines in the drawings depict portions of the table light that form no part of the claimed design.

1 Claim, 8 Drawing Sheets(56)
